(57) **CLAIM**

The ornamental design for an adjustable height basketball hoop, as shown and described herein.

DESCRIPTION

FIG. 1 is a perspective view of the invention;

FIG. 2 is a front view thereof;

FIG. 3 is a rear view thereof;

FIG. 4 is a right side view thereof;

FIG. 5 is a left side view thereof;

FIG. 6 is a side view thereof with the upper arm in a lowered position.

FIG. 7 is a top view of FIGS. 1-6; and,

FIG. 8 is a bottom view of FIGS. 1-6.

The broken lines are included for the purpose of illustrating portions of the adjustable basketball hoop that form no part of the claimed design.
